CONVERTIBLE COUCH

Andrew Roth, Philadelphia, Pa.

Application January 7, 1942, Serial No. 425,807

6 Claims. (Cl. 5—17)

This invention relates generally to beds of the couch or davenport type and more particularly to a construction thereof which enables the couch to be converted into a double bed.

It is among the principal objects of the present invention to provide a convertible couch of the character just stated which is of simple and inexpensive construction, which is sturdy and neat in appearance, and which may be readily transformed for use as a double bed, the construction of the couch being such that it normally resembles in appearance the conventional type of couch or davenport now in extensive use.

Other objects and advantages of the present invention will appear more fully hereinafter, it being understood that the invention consists substantially in the combination, construction, location and relative arrangement of parts; all as described in detail hereinafter, as shown in the accompanying drawings and as finally pointed out in the appended claims.

In the accompanying drawings, which are illustrative of a preferred construction of the present invention,

Figure 1 is a perspective view of the unit constructed in accordance with and embodying the principles of the present invention, the unit as shown in this figure being set up for normal use as an ordinary couch or davenport;

Figure 2 is a perspective view showing the under-structure of the couch partially extended for converting the couch for use as a double bed;

Figure 3 is a perspective view of the unit set up for use as a double bed;

Figure 4 is an end elevational view of the unit with parts thereof shown in section;

Figure 5 is a horizontal sectional view of a part of the under-structure taken along the lines 5—5 of Figure 4;

Figure 6 is a vertical sectional view of the under-structure taken substantially along the lines 6—6 of Figure 5;

Figure 7 is a perspective view showing certain constructional details of the under-structure of the couch unit; and

Figure 8 is a sectional view showing a detail of the pivot construction.

Essentially, the couch unit of the present invention consists of an under-structure or foundation made up of a rigid frame which is normally stationary in position, and a pair of movable frame sections which are each pivoted to the stationary frame in such manner that they may be each rotated through an angle of approximately 90° so as to project them in extended parallel relation

frontally of the fixed frame of the couch unit to provide a bedstead of a size and shape approximating that of the conventional double bed. An important feature of the construction of the present invention resides in the fact that the movable frame members are relatively so proportioned that when they are extended into position to form the double bedstead, the long or sleeping axis of the bed parallels the long axis of the couch. Consequently, it is only necessary to shift one of the couch mattresses laterally of its normal position on the couch to cover the extended portions of the movable frames. The single mattress so shifted is one of the two mattresses with which the couch is normally provided, and in view of the fact that the second mattress need not be moved when the couch is converted into the double bed, it may be secured permanently to the fixed frame of the couch understructure or chassis.

Referring now more particularly to the drawings, it will be observed that the unit of the present invention includes a supporting under-structure designated generally by the reference numeral 10 upon which is normally disposed a pair of superimposed mattresses 11 and 12. When the unit is employed as a conventional couch, it may be placed flat against a wall, as shown in Figure 4, in which case several back cushions 13 may be employed to provide back rests for persons who may occupy the couch in sitting positions. These back rest cushions 13 are, of course, individually removable and form no part of the present invention.

The supporting structure for the mattresses 11 and 12 includes a pair of vertically spaced main frame members 14 and 15 which are each of substantially rectangular construction and arranged in vertically spaced relation. These frame members 14 and 15 constitute the fixed or stationary parts of the unit and are secured together along their longitudinally extending rear edges by flat spacing member 16. The lower frame member 14 is fitted at each of its four corners with a supporting leg 17, while the upper frame members 15 supports the lower fixed mattress 11. It will be noted in this connection that the said mattress 11 is upholstered to the frame 15 so that the covering material for the mattress 11 extends about and conceals from view the marginal edges of the upper frame 15. Preferably, the mattress 11, as also the upper mattress 12, is of the inner-spring construction, thus dispensing with the need for any spring or other such resilient suspension within the frame 15 itself. However, if

desired, the mattress 11 need not be upholstered to the frame 15, but instead may be formed as a separate removable type of cushion mattress, and the frame 15 may be provided with a suitable resilient support within the confines thereof for resiliently supporting the cushion mattress.

Interposed between the vertically spaced, fixed frame members 14 and 15 are a pair of movable frames 18 and 19, these latter being shown more particularly in Figures 5 and 6. As appears most clearly in Figure 5, these movable frame members 18 and 19 are each of approximately square formation and are respectively pivoted between the fixed frame members 14 and 15 by the vertically extending pivot pins 20 and 21 fixed in the front longitudinals of the said frames 14 and 15. The intermediate frame members 18 and 19 may thus be rotated about their respective pivot pins 20 and 21 in the direction of the arrows shown in Figure 5 through angles of approximately 90°, both of the frame members 18 and 19 being shiftable in a common horizontal plane from their position, as shown in Figures 1 and 5, into their extended positions, as shown in Figures 2 and 3.

It will be apparent that the intermediate movable frame members 18 and 19 serve to maintain the fixed frame members 14 and 15 in vertically spaced relation. In addition, if desired, the pivot pins 20 and 21 may be provided with spacer collars 21^a to insure proper vertical spacing between the front edges of the fixed frame members 14 and 15.

The outer edges of each of the movable frame members 18 and 19 are provided in each case with upwardly extending flanges 22 and 23, which flanges serve normally when the unit is set up for use as a couch (see Figure 1) to embrace and cover the opposite ends of the lower mattress and so serve as a decorative trim at the opposite ends of the couch. When the movable frame members 18 and 19 are swung outwardly to convert the couch into a double bed, these flanges 22 and 23 serve as end stops for the second mattress 12 when the latter is placed upon the extended frames. If desired, of course, the flanges 22 and 23 may be dispensed with without affecting the operating efficiency of the unit. Preferably, the movable frame members 18 and 19 are each fitted with a supporting panel 24 of any suitable material, such as ply wood, canvas or the like, or these frames may be fitted with any suitable resilient support for the mattress which is superimposed thereon. The opposite free corners of each movable frame are each provided with a supporting leg 25, these legs being relatively so placed as to clear the supporting legs 17 of the stationary frame when the movable frame members 18 and 19 are swung into closed position, as shown, for example, in Figure 1.

Inasmuch as the conventional couch is normally of a length more than twice that of its width, the width of the couch being normally such as to provide for comfortable seating of a person thereon with his back against the cushions 13, it will be observed that in the unit of the present invention the width of each of the movable frame members 18 and 19 substantially equals the normal width of the couch. Consequently, when these movable members 18 and 19 are swung into their extended positions, as shown in Figures 2 and 3, their combined widths do not equal the length of the couch, the movable members being relatively so pivoted to the fixed under-structure of the couch as to leave a space between the movable members when they are ex-

tended in parallel relation frontally of the couch. This space is approximately equal to the difference between the overall length of the couch and the combined widths of the extended movable members. To fill this space between the extended movable members there is provided an extensible panel 26, this panel being normally disposed beneath the unit when the latter is set up as a couch, as shown in Figure 1, and adapted to be extended forwardly of the couch, as shown in Figure 2, when the unit is set up as a double bed. As appears most clearly in Figures 2, 6 and 7, this extensible intermediate member 26 is under cut along its opposite longitudinally extending edges, as at 27, to provide an inverted rabbet. The front and inner-side edges of each of the movable frame members 18 and 19 are complementally rabbeted, as at 28 and 29, to provide laterally projecting flanges which underlie and serve as supports for the laterally extending flanges of the intermediate member 26. Thus, when the unit is set up as a couch, as shown, for example, in Figure 1, the intermediate member 26 is supported between the frame members 18 and 19 by the interengagement of the lateral flanges of the member 26 with the flanges 28-29 of the said frame members. On the other hand, when the frame members are swung into extended position, as shown in Figure 3, the intermediate member 26 is extended frontally of the couch and is supported between the frame members by the interengagement of the lateral flanges of the member 26 with the flanges 28-28 of the extended frame members.

Not only does the intermediate member 26 serve to fill the space normally existing between the extended frame members 18 and 19, but it also serves to maintain the latter in parallel relation. In order to prevent unintentional spreading of the extended frame members away from each other, a detent 30 is pivoted, as at 31, to one of the movable frame members, the free end of the detent being kerfed, as at 32, for engagement with a pin 33 provided in the other of said movable frame members. Thus, the detent 30 serves to lock the extended frame members together, as shown in Figure 3. It will be understood, of course, that when the movable frame members 18 and 19 are extended into open position, all that is necessary to complete the double bed set up is to shift the upper mattress 12 forwardly of the lower fixed mattress 11 and on to the extended frame, as shown in Figure 3, the sleeping pillows 34 being then arranged as shown.

It will be understood, of course, that the invention is capable to various changes and modifications which may be made from time to time without departing from the real spirit or general principles thereof, and it is accordingly intended to claim the invention broadly, as well as specifically, as indicated in the appended claims.

What is claimed as new and useful is:

1. In a convertible couch, an under-structure consisting of a pair of relatively fixed vertically spaced main frames and a pair of auxiliary frames disposed in a common plane and respectively fitted between said main frames at opposite ends of the latter, said auxiliary frames being pivoted to the main frames whereby to permit said auxiliary frames to be rotated in the common plane of said auxiliary frames into a position where said latter frames extend in parallel relation frontally of said main frames, the couch under-structure being thus widened to accom-

modate a pair of mattresses disposed in co-planar relation.

2. In a convertible couch, an under-structure therefor including a pair of vertically spaced substantially rectangular main frame members, a pair of auxiliary frame members nested between said main frame members, and pivot means interconnecting each of said auxiliary frame members with the main frame members, said pivot means being located adjacent the frontal edge of the under-structure and intermediate the opposite ends thereof whereby to permit said auxiliary frames to be rotated respectively through angles of approximately ninety degrees and in directions toward and away from each other.

3. In a convertible couch, an under-structure therefor including a pair of vertically spaced relatively fixed main frame members, a pair of movable frame members nested between said main frame members, said movable frame members being arranged in co-planar relation and each occupying less than half the area of the main frame members, said movable frame members being pivoted to the main frame members for rotation toward and away from each other through angles of approximately ninety degrees, and an auxiliary member also nested between said frame members and adapted to occupy the free space between said movable members.

4. In a convertible couch, an under-structure therefor including a pair of vertically spaced relatively fixed main frame members, a pair of movable frame members nested between said main frame members, said movable frame members being arranged in co-planar relation with their front, outer and rear edges normally disposed flush with the corresponding edges of the main frame members, said movable frame members being each of a length somewhat less than half the overall length of the main frame members whereby to provide a space between the inner ends of said movable members, pivot means interconnecting each of the movable members with the main members to permit the former to be rotated toward and away from each other through angles of approximately ninety degrees,

and an auxiliary member nested between said main members and adapted to occupy the space provided between said movable members when the latter are positioned between said main members, said auxiliary member being shiftable forwardly of the main members to fit between said movable members when the latter are rotated into positions extending frontally of the said main members of the couch under-structure.

5. In a convertible couch, a relatively fixed main supporting frame for a pair of superposed couch mattresses, said frame including a pair of vertically spaced members, a pair of movable frames respectively disposed between said vertically spaced members of the frame and pivoted thereto for rotation from positions within the confines of the relatively fixed main frame to positions extending freely from the front thereof, said movable frames being each of a size and shape that when fully nested between the spaced members of the main frame, the frontal edges of all of said nested frames are substantially disposed in a common vertical plane, the arrangement being further such that when said movable frames are freely extended with respect to said main frame, they conjointly provide a support for one of said couch mattresses with the upper surface of the latter disposed in substantially co-planar relation with respect to that of the other mattress.

6. In a convertible couch of the character defined in claim 5 wherein said movable frames are relatively of such size and so pivoted with respect to the main frame as to leave a free space therebetween when the same are swung into their freely extending mattress-supporting positions, said couch including an auxiliary co-planar member slidably disposed between the spaced members of the main frame and adapted to be extended from its normal retracted position to occupy said space to provide a central support for the mattress, and means on said pivoted members for supporting said auxiliary member in either of its retracted or extended positions.

45 ANDREW ROTH.
